J. B. SINGER AND A. B. LEVY.

DISPLAY CARTON.

APPLICATION FILED FEB. 24, 1919.

1,361,630.

Patented Dec. 7, 1920

INVENTORS:
Joseph B. Singer and Arthur B. Levy
or C. P. Goepel ATTORNEY

UNITED STATES PATENT OFFICE.

JOSEPH B. SINGER, OF BROOKLYN, AND ARTHUR B. LEVY, OF NEW YORK, N. Y.

DISPLAY-CARTON.

1,361,630.

Specification of Letters Patent. Patented Dec. 7, 1920.

Application filed February 24, 1919. Serial No. 278,785.

To all whom it may concern:

Be it known that we, JOSEPH B. SINGER and ARTHUR B. LEVY, citizens of the United States, the former a resident of the borough of Brooklyn, county of Kings, city and State of New York, and the latter a resident of the borough of Manhattan, city, county, and State of New York, have invented certain new and useful Improvements in Display-
5 Cartons, of which the following is a speci-
10 fication.

The present invention relates to improvements in display cartons, and has for an object to provide a device of this character having means for supporting the container portion in inclined position when the carton is open and displayed upon a counter or the like. Further objects of the invention are to provide such a device in which the inclining or supporting means may be carried by the carton in such manner as to be inconspicuous and non-projecting when the carton is not displayed, or during shipping, which will not require any skill or special knowledge to set up, will be simple and inexpensive and may be combined with any of the usual types of containers or boxes. It is further proposed to provide by such means an effectual advertising or display surface in relation to the carton. A further object is to provide in one embodiment a supporting means which will automatically move toward or assume its supporting position.

30

With these and other objects in view, embodiments of our invention are shown in the accompanying drawings and these embodiments will be hereinafter more fully described with reference thereto, and the invention will be finally pointed out in the
35 claims.

In the accompanying drawings:

Figure 1 is a perspective view of one embodiment of our invention, the same being folded or covered to be shipped or stored;

Fig. 2 is a similar view with the cover removed;

Fig. 3 is a perspective view showing the same in display position;

Fig. 4 is a plan view of the blank from which the supporting member is formed;

Fig. 5 is a transverse sectional view of the carton in the position shown in Fig. 2;

Fig. 6 is a similar view of the same in the position shown in Fig. 3;

Fig. 7 is a perspective view of a modified form in non-display position;

Fig. 8 shows the same in inclined or display position;

Fig. 9 is a perspective view of a further modified form in non-display position; and
60

Fig. 10 shows the same in inclined or display position.

Similar reference characters indicate corresponding parts throughout the several figures of the drawings.
65

Referring to Figs. 1 to 6, the embodiment of our invention shown therein, comprises a box or container A of any suitable construction and design and in the present illustration formed of cardboard and folded to shape, the same being preferably of one piece and held in set-up position by the end flaps 21 and 22 folded over the open ends 23 of the sides 24 and 25, the flaps 21 and 22 being caught beneath struck-up tabs 26 and 27 in the bottom of the container. This is an arbitrary form, however, as far as the invention is concerned and as above remarked, other suitable designs of boxes or containers may be employed in connection with the invention. To the rear side 24 of the container A, there is pasted the flap 28 of a display member 29 adapted to have printed on its front side suitable advertising matter relative to the goods contained in the carton. In the folded position of the device, this member folds down flat upon the upper surface of the contents forming a cover therefor, at the same time protecting its printed display surface.

90

The inclining and supporting member B shown in its flat blanked out form in Fig. 4, comprises a rectangular portion 30 having at its upper longitudinal edge, a pasting flap 31, and provided at its ends with end flaps 32 and 33 having their edges inclined toward the front edge of the portion 30. Foldable extensions 34 and 35 project from the lower edge of the flaps 32 and 33, while a side forming portion 36 foldable upon itself along the longitudinal score line 37, and provided with a longitudinal flap 38 extends downwardly from the lower edge of the portion 30. In setting up the member B, the flaps 32 and 33 are folded upwardly, the extensions 34 and 35 being folded inwardly along the longitudinal lower edge of the portion 30, the extensions being then held by the side forming portion 36, which is folded upon itself over the said extensions, 105 its flap 38 being caught beneath the struck-up tab 39. The member B is then placed

over the bottom of the container A and is hingedly secured thereto by pasting the flap 31 to the bottom substantially along the central line parallel to the longitudinal edges 5 of the portion 30, the member B overlying substantially half of the bottom of the container while the ends 32 and 33 and the side 36 engage over the ends and the side of the container. As shown in Fig. 1, the carton 10 in its folded non-display position may be slid into a tubular shaped cover 40, or it may if desired be provided with any suitable form of cover to protect the same when being shipped or when not displayed upon a 15 counter.

In display position, the member 29 is raised to expose its printed side and the member B is folded back so that it occupies a reverse position to that occupied when 20 folded, in which position the portion 30 engages the bottom of the container and the ends 32 and 33 support the container in inclined and display position, the inclined edges of the said ends in display position 25 being in a plane passing through the front lower edge of the said container A. The surface of the carton, as well as the exposed surfaces of the member B may contain any suitable advertising matter, the same being 30 of such form that only one side of the blank need be prepared for receiving printing. This device is compact when not displayed and may be readily set up without requiring any special operation other than the folding 35 back of the member B, that is, it does not require the connecting of any parts, the insertion of tongues or other complicated means, which features make the setting up of such devices tedious and are usually overlooked by the average storekeeper with the 40 result that such display devices are not always properly set up.

In Figs. 7 and 8, we have illustrated a slightly modified form in which the supporting member B is secured to the side of a container C and in display position is swung forwardly as shown in Fig. 8, the open side of the container in this case being 45 the front side in display position rather than the top side as in the foregoing form of our 50 invention.

In the form shown in Figs. 9 and 10, the pasting flap 31 of the member B is folded upon the portion 30 in the non-display position 55 occupying a reverse position from that of the form shown in Figs. 1 to 8. With this construction the inherent springiness of the material will cause the member B to be automatically swung away from the folded 60 position when removed from the cover toward or to the display position as shown in Fig. 10. It will be understood that this feature may also be employed in connection

with the form of our invention shown in Figs. 1 to 5.

We have illustrated and described preferred and satisfactory embodiments of our invention, but it will be obvious that changes may be made therein within the spirit and scope thereof as defined in the appended 70 claims.

We claim:

1. A display stand adapted for attachment to a container and comprising a one-pieced blank having a base, lateral and end portions, said portions being adapted to be folded into position to upstand from one side of the base, said blank having interlocking means integral therewith adapted to be interengaged when said lateral and end portions are bent up from the base to maintain the lateral and end portions in set up position, said blank having a projecting pasting flap along the free edge of said base being adapted to be secured to said container in 80 position for engaging the base flat against a side of the container and with said lateral and end portions of the base embracing the container, said base being adapted to be swung into supporting position and said 90 lateral and end portions being adapted to project downwardly from the base in such position for supporting the container in an inclined position, said lateral and end portions of the base being adapted to be released 95 from each other and swung into the plane of the base for packaging said display stands and for disposing the display stands in flat position.

2. A display stand adapted for attachment to containers of the knock-down type and comprising a single blank having a base, lateral and end portions, said lateral and end portions being adapted to be bent upwardly from the base to provide supporting 100 means for holding the base in an inclined position when on display to support the container when set up in an inclined position, said blank also having interlocking means adapted to retain the lateral and end 105 portions of the base in bent up position and being releasable whereby when said container is knocked down into flat position said display stand may be knocked down in flat position for packaging the display 110 stands with the containers in relatively large numbers said blank provided along one free longitudinal edge with a pasting flap 115 adapted to swing at its line of emergence with said base.

In testimony that we claim the foregoing as our invention, we have signed our names hereunder.

JOSEPH B. SINGER.
ARTHUR B. LEVY.
